UNITED STATES PATENT OFFICE.

EDWARD B. CLARK, OF KNOXVILLE, PENNSYLVANIA, ASSIGNOR OF ONE-HALF TO
GEORGE C. CHAMBERS, OF SEWICKLEY, PENNSYLVANIA.

METHOD OF PRODUCING CAST TABLETS.

1,413,261.

Specification of Letters Patent. Patented Apr. 18, 1922.

Application filed December 15, 1920. Serial No. 430,875.

To all whom it may concern:

Be it known that I, EDWARD B. CLARK, residing at Knoxville, in the county of Allegheny and State of Pennsylvania, a citizen of the United States, have invented or discovered certain new and useful Improvements in Methods of Producing Cast Tablets, of which improvements the following is a specification.

10 My invention relates to the production of tablets, such as those commonly set up in large office buildings as directories of tenants, and those now being widely erected in public and quasi public places, bearing 15 the names of men who have served in the recent war. The invention consists in a method of production, whereby tablets of relatively costly and not easily worked moldable material, such for example as bronze, 20 bearing legible characters, may be produced at relatively small expense.

While I am primarily concerned with the production of bronze tablets, it will be understood that the invention is generally applicable to the making of tablets of any moldable material—of type metal for example, or of plaster or of celluloid.

The invention consists in building, unit upon unit, the pattern from which the matrix is to be formed. By making provision, 30 that each succeeding unit may within a wide range bear any desired character, it becomes possible to produce any legend one desires, and to reproduce this legend in the 35 finished tablet—all by mechanical operations of simplest sort.

In the accompanying drawings Fig. I shows in front elevation such a tablet as it is the object of my invention to produce; 40 Fig. II shows in perspective a line which constitutes a pattern unit, as I shall presently describe.

The invention consists, first, in assembling in a linotype machine, a line of matrices bearing legible characters in reverse; second, in the further operation of the machine, casting from the line of matrices so assembled a line bearing the characters in obverse; third, employing the line so cast 50 as a unit in building up a pattern; and, finally, producing the tablet from the pattern in the usual manner.

The use of the linotype machine in the practice of my invention involves these de-

partures from normal linotype machine use; 55 first the matrices are specially prepared; the legible characters which they bear are formed, not as in linotype practice in obverse but in reverse; the characters upon the line which is cast in the machine are not, 60 in the usual reverse position, but in obverse. And it is further to be remarked that the thing ultimately produced is not a plate for printing—a mere instrument by the use of which something else is to be obtained, 65 namely, a printed page; but it itself, namely the cast tablet, is the ultimate product, existing for itself alone.

In normal use the linotype machine in assembling the matrices from which the line 70 of type is cast, aligns them along the upper edges of the letters. Different fonts of type involve the use of differently proportioned matrices. It follows that in practical service in printing establishments the use of the 75 linotype machine is confined to typesetting from a single font of type. To the extent that other type are required to be used, hand setting is resorted to.

The matrices from which the lines are 80 cast to make up a pattern for my tablet bear characters which in form are the reverse of the characters of type matrices. It follows that the matrices assembled in the linotype machine are aligned along the lower edges 85 of the letters. Being so aligned the relative proportions of matrices assembled together in a line cease to be a disturbing factor, and matrices of various fonts may be brought together in the operation of the machine and 90 there is no need to resort to hand setting.

Referring to the accompanying drawing, a tablet is there illustrated such as my invention will produce. The tablet will be seen to bear lines of legible characters, 95 names, etc. Each of these lines of legible characters may be produced from a pattern made in a linotype machine Fig. II, for instance shows the pattern unit for the first line, which in this instance happens to be the word 100 Knoxville. Such a unit as is shown in Fig. II may manifestly be produced with a linotype machine, employing matrices which as compared with matrices used for printing bear legible characters in reverse. Such 105 units as Fig. II shows so produced for the various lines may be assembled with blank blocks, ornamental borders, medallions,

raised lines, and the like, and the whole made into a complete pattern.

From the pattern so prepared and assembled the matrix for the ultimate casting 5 may be produced, and casting will follow in the usual manner of proceeding.

In the pattern as well as in the matrix for the ultimate casting opportunity is afforded for hand work, eradicating seams and 10 blemishes, artistic embellishments, etc.

As I have already intimated, the use of the linotype machine in practicing my invention is not limited to lines set from matrices of a single font, but matrices of 15 different sizes may be assembled to form a single line.

Not all the characters in a line need be legible, but legible characters are essentially involved in the practice of the invention.

20 The characters upon the matrices of the linotype machine may be formed in intaglio or in relief, and correspondingly the characters upon the ultimate tablet will appear in relief or in intaglio.

25 The surface of the ultimate casting may be worked over polished, colored, enameled, or gilded, as desired.

I claim as my invention:

1. The herein described method of producing memorial tablets and like articles which consists in assembling a plurality of blocks bearing legible characters in reverse in line, casting an integral line in the matrix so assembled, employing such casting as the pattern unit in making a complete 30 pattern, producing a mold from such pattern, and casting the desired article in the mold so prepared.

2. The herein described method of producing a pattern for a memorial tablet or like article which consists in assembling a plurality of blocks bearing legible characters in reverse in a line, casting an integral line in the matrix so assembled and employing the line so cast as a unit together with other units in the building up 35 of the pattern.

In testimony whereof I have hereunto set my hand.

EDWARD B. CLARK.
